UNITED STATES PATENT OFFICE.

JOHN W. McAULIFFE, OF PELHAM, NEW YORK.

CIGAR WITH SELF-CONTAINED HOLDER.

1,312,490.

Specification of Letters Patent.

Patented Aug. 5, 1919.

Application filed April 26, 1919. Serial No. 292,781.

To all whom it may concern:

Be it known that I, JOHN W. McAULIFFE, a citizen of the United States, residing at town of Pelham, county of Westchester, 5 and State of New York, have invented a certain new and useful Improvement in Cigars with Self-Contained Holders, and declare the following to be a full, clear, and exact description of the same, such as will 10 enable others skilled in the art to which it pertains to make and use the same, reference being had to the accompanying drawings, which form a part of this specification.

15 My invention has for its object to combine with a cigar a holder or mouthpiece which will permit the entire cigar to be consumed instead of making it necessary to throw away a part of it.

20 A further object of the present invention is to produce a combined cigar and mouthpiece or holder which shall be simple in construction, neat in appearance, and of sufficient mechanical strength to insure that 25 there will be no derangement or loosening of the parts when handled in the same way that cigars are usually handled up to the time they are ignited by the consumer.

A further object of the present invention 30 is to produce a simple and novel device of the character specified which can readily be applied by the cigar maker during the operation of making the cigar, without inconvenience to him, and without interfering with the process of making the cigar.

The various features of novelty whereby my invention is characterized will herein-after be pointed out with particularity in the claims; but, for a full understanding 40 of my invention and of its objects and advantages, reference may be had to the following detailed description taken in connection with the accompanying drawing, wherein:

45 Figure 1 is a side elevation of a combined cigar and holder arranged in accordance with one form of my invention;

Fig. 2 is a longitudinal sectional view of the butt end of the unwrapped cigar having 50 the cup-shaped holder applied thereto, and the fastener for the holder and the mouthpiece being shown detached;

Fig. 3 is a view partly in section and 55 partly in elevation of the butt end of the completed cigar; and

Fig. 4 is an end view of the cup-shaped holder.

Referring to the drawing, 1 and 2 represent two halves of a cup-shaped device having a perforated stem, 3, projecting axially from the bottom thereof; the plane of division being preferably through the longitudinal center so as to divide the device into two equal halves, each comprising one-half of the cup and one-half of the stem. The 60 cup is preferably made of a non-combustible material, conveniently metal. The cup is provided with an annular inwardly projecting rib or bead, 4, preferably formed in such a manner that no depression is left on 70 the external surface of the cup. This may conveniently be accomplished by forming the halves of the cup of soft metal pressed into shape between suitable dies.

The external contour of the cup is made 75 of a size and shape to correspond to the size and shape of the unwrapped bunch or body, 5, of the cigar to which the mouthpiece is to be applied, in the vicinity of the butt end of such bunch or body. The 80 cigar maker proceeds to make the member 5 in the usual way and he then places the two halves of the cup in position on the butt end, as shown in Fig. 2; this operation causing the damp tobacco to be compressed 85 and the rib or bead to form for itself a seat or groove. A small bushing, 6, threaded externally and also internally, is then screwed upon the screw threaded stem, fastening the two parts of the cup together and 90 making it impossible for the cup to become loose or to be accidentally disengaged from the cigar without destroying the latter. After the body or bunch has been made and the cup fastened thereto, the wrapper 95 7 is applied in the usual way, being carried back over the cup and folded inwardly against the bottom as indicated at 8. A mouthpiece, 9, of cork or other suitable material is then screwed upon the bushing, 100 clamping the free end of the wrapper between it and the bottom of the cup and thus holding the end of the wrapper securely in place.

While I have illustrated and described 105 with particularity only a single preferred form of my invention, I do not desire to be limited to the exact structural details thus illustrated and described; but intend to cover all forms and arrangements which 110

come within the terms employed in the definitions of my invention constituting the appended claims.

I claim:

- 5 1. An attachment for a cigar comprising a cup having a downwardly projecting stem, the cup and stem being divided longitudinally into a plurality of parts, and means engaging with said stem for holding said 10 parts together.
  2. In a device of the character described, a cup-shaped member having a downwardly projecting stem, and inwardly projecting means in the interior thereof adapted to embed itself in a cigar, said member being divided longitudinally into a plurality of parts, and means adapted to engage with said stem to hold said parts together.
  3. In a device of the character described, 20 a cup-shaped member having inwardly projecting means in the interior thereof adapted to embed itself into a cigar, said member being divided longitudinally into a plurality of parts, and means for detachably securing 25 said parts together.
  4. In a device of the character described, a cup-shaped member having a stem, said member including the stem being divided longitudinally, a bushing adapted to be
- slipped over said stem, and a mouthpiece 35 adapted to be applied over said bushing.
5. In a device of the character described, a cup-shaped member having a stem, said member including the stem being divided longitudinally, a bushing adapted to be 35 screwed upon said stem, and a mouthpiece adapted to be screwed upon said bushing.
6. A cigar having the butt end inclosed in a cup, said cup being divided longitudinally, and a mouthpiece coöperating with 40 said cup to hold the parts thereof together.
7. A cigar having the butt end inclosed in a cup, said cup being divided longitudinally and having an inwardly projecting portion embedded into the body of the cigar, 45 and a mouthpiece attached to said cup and holding the parts thereof together.
8. A cigar having a cup closing the butt end of the body thereof, a wrapper extending over the body and sides of the cup and 50 folded over the bottom of the cup, a mouthpiece, and means for attaching the mouthpiece to the cup in a manner to clamp the end of the wrapper between it and the cup.

In testimony whereof, I sign this specification.

JOHN W. McAULIFFE.
